UNITED STATES PATENT OFFICE.

ROUSE K. BREWSTER, OF KINGSTON, NEW YORK, ASSIGNOR, BY MESNE ASSIGNMENTS,
TO HERCULES EXPLOSIVES CORPORATION, OF WILMINGTON, DELAWARE, A COR-
PORATION OF NEW YORK.

POCKET MAGNETO.

Application filed June 24, 1920. Serial No. 391,468.

To all whom it may concern:

Be it known that I, ROUSE K. BREWSTER, a citizen of the United States, residing at Kingston, in the county of Ulster and State 5 of New York, have invented new and useful Improvements in Pocket Magneto's, of which the following is a specification.

This invention relates to portable or pocket electric generators of the type employed for the purpose of firing mines, etc., which are known to the trade as "pocket batteries," "pocket generators" or "pocket dynamos."

The objects of the invention are to provide a structure of the type set forth which shall consist of few parts, which shall not be liable to derangement of parts, and which shall be safe, certain, and otherwise efficient in use, and which may be handled 20 and operated with the utmost degree of efficiency by the unskilled laborer or operator.

With the above and further objects in view, my invention consists in certain features of structure, combination and relation which will be more fully set forth herein-after.

I have illustrated one embodiment of my invention in the accompanying drawings, 30 wherein:—

Figure 1 is a longitudinal vertical section through my improved generator.

Figure 2 is a horizontal section taken on lines 2—2 of Figure 1.

Figure 3 is a transverse vertical section taken on lines 3—3 of Figure 1.

Figure 4 is a transverse vertical section taken on lines 4—4 of Figure 1.

Figure 5 is a transverse vertical section 40 taken on lines 5—5 of Figure 1.

Figure 6 is a transverse vertical section taken on lines 6—6 of Figure 1.

Figure 7 is an end elevation of the apparatus with the operating handle removed.

Referring to the drawings wherein similar numerals denote like parts throughout the several views:

1 denotes the casing of the machine which may be of any suitable shape or form, but 50 which it is preferred to construct so that the apparatus may be readily carried in the pocket of the operator. In this casing are mounted magnets 2, which, as shown, are preferably of the horseshoe type, and have

pole pieces 3. An armature 4 is mounted 55 within the pole plates of the magnet 2. This armature carries the usual insulated wire windings, one end of which is connected to the armature metal or grounded to the machine, the other end making contact with the brush 5, whence the current induced is carried by any suitable means to binding post 6, this post being insulated from the machine.

The end plate 7 of the armature carries 65 a pinion 8. This pinion meshes with a gear 9 mounted within the casing, which gear is actuated by means of a ratchet pinion 10 mounted therein.

The accelerator and actuating device 11 70 includes an externally-toothed gear 13, and is formed as a hollow drum having an end-cap 14 screw-threaded and locked thereon; the whole being mounted on the shaft 12 and free to turn thereon within certain limits. A coil spring 15 is positioned within the drum, one end of the spring being affixed to shaft 12, and the other end connected on the casing of the drum 11 by means of a fastening device such as the 80 stud 16.

A cam yoke 17 is pivoted, as at 18, to the outer end of the drum casing 14. This cam yoke is formed with a flanged contact member 19 and is actuated through means of 85 a cam 20 which is affixed to shaft 12. A fixed contact member 21 surrounds shaft 12 and is secured to the wall of the casing. This fixed contact member is formed with bevelled contact arms 22. The fixed contact member is insulated by any of the usual means and is connected by suitable wiring to binding post 23. Shaft 12 and its associated members are rotated through 90 means of a usual handle 24.

In the operation of the device the handle 24 is turned counter-clockwise. As the generator and its driving parts have considerable inertia, the movement of handle 24 is not immediately communicated to the generator, but operates through half a turn to wind up the spring 15, and to break the contacts 19—22, by reason of the relative movement of shaft 12, carrying cam 20, and cover 14, carrying cam yoke 17. As 105 100 the turning movement of the handle 24 is continued the spring 15 unwinds half a turn, closing contacts 19—22 after the

generator has been brought up to full speed by continued turning of the handle 24. During current production the driving of the generator is exclusively by handle 24 which is turned counter-clockwise at a uniform rate, and the contact parts have the relative position shown in Figure 3.

Rotation of gear 13 results in actuation of the armature 4 which continues until 10 the contact on the cam yoke again engages the fixed contact member which closes the circuit and permits the current generated by the revolving of the armature to be discharged into the line.

15 It is apparent that a device is provided which is certain and positive in operation, and which generates a uniform current no matter how handled.

I claim:—

20 In combination with a dynamo, having a spring drum for operating the armature

thereof, a shaft on which said drum is rotatably mounted, a spring in said drum connecting said shaft with the walls of the drum, a casing surrounding the dynamo and 25 spring drum, a cam yoke pivoted at one end to the drum and having an elongated slot formed therein at its opposite end, said slot receiving said shaft, said yoke having a contact member thereon, a contact 30 member attached to the casing, and a cam secured eccentrically to said shaft and adapted to move the contact member on said yoke into and out of contact with the contact member on said casing.

35 In testimony whereof I have hereunto set my hand in presence of two subscribing witnesses.

ROUSE K. BREWSTER.
